Attorney

UNITED STATES PATENT OFFICE

HARRY T. HIPWELL, OF PITTSBURGH, PENNSYLVANIA

FLASH LAMP

Application filed April 19, 1928. Serial No. 271,170.

My invention relates to lamps and more particularly to what are commonly designated as flash lamps which involve the employment of dry cells and a filament lamp mounted in a casing, together with suitable circuit-controlling means.

One object of my invention is to provide a flash lamp having an improved form of cover or cap for the casing which contains the dry cells.

Another object of my invention is to provide a lamp structure wherein the retaining spring for holding the dry cells in place and for grounding the electrical circuit serves also to perform other functions.

A further object of my invention is to provide an improved form of connection between the cap and the casing.

Another object of my invention is to provide an improved form of suspending device on the cap whereby the lamp may be hung upon a hook or other support.

Still another object of my invention is to generally simplify and improve lamp structures of the character referred to.

Some of the forms which my invention may take are shown in the accompanying drawing, wherein Figure 1 is a perspective view of a lamp with the suspending device in open or upright position; Fig. 2 is a plan view of the structure of Fig. 1; Fig. 3 is a view similar to Fig. 2, but showing the suspending device in closed position; Fig. 4 is a fragmentary longitudinal sectional view of the structure of Fig. 1, with the suspending device partially open; Fig. 5 is a similar view, but showing the suspending device closed; Fig. 6 is a view similar to Fig. 5, but showing a modified form of connection between the cap member and the casing, and Fig. 7 is a perspective view showing the cap member of Fig. 6 removed from the casing.

Referring to Figs. 1 to 5, I show a casing 8, which may be of somewhat the usual form, carrying a lens 9 and a suitable lamp bulb (not shown). A cap 10 has screw-threaded connection with the casing 8 to render it conveniently detachable for permitting replacement and removal of the dry cells 12 (Fig. 5) in the usual manner.

A spring 11 seats at its outer end within the cap 10 and at its inner end bears against the outer terminal of the dry cell 12, to serve as a ground connection for the cell and to hold the cells against rattling movement within the casing.

A suspending member 13 is provided with integrally-formed tongues at its edge, one of said tongues being bent to form a knuckle or eye 14 through which one end of the spring 11 projects, to form a hinge joint, so that the member 13 will have pivotal movement upon the cap 10. This connection also serves to retain the spring in position in the cap 10, since the knuckle 14 projects through an opening in one corner of the cap. The other tongue 15 is bent to lip form to serve as a catch or snap fastening when the member 13 is folded against the cap, as shown in Fig. 5. When the member 13 is folded, it will displace the end turn of the spring 11 slightly to compress the same radially, and thereby cause the catch 15 to be yieldably held in snug engagement with the rim of the casing, thus producing a snap action without the necessity of flexing the catch 15.

The suspending member 13 is cut out, as shown at 16 so that when opened, it may be readily hung upon a hook or a button, the reduced portion of the cut-out portion serving to prevent accidental displacement from a button or other hook-like support. The casing 10 has a raised portion 17 about which the cut-out portion 16 of the suspending member 13 fits when the lip is closed, as shown in Fig. 3, thus securely holding the member 13 against displacement radially when it is closed.

In Figs. 6 and 7, I show a structure wherein the cap 10^a is of slightly different form than the cap 10, particularly with respect to the manner in which connection is effected with the casing 8^a. Instead of having screw-threaded connection with the casing, the cap 10^a is provided with bayonet slots 19, which, when the cap is placed in position and turned slightly, interlock with pins 20 that are mounted in the sides of the casing. The closed ends of the slots are notched slightly to provide seats for the pins 20. The spring

11, in addition to serving as a hinge mounting for the suspending device 17 also exerts outward pressure upon the cap 10^a to yieldably hold the bayonet joint parts in locked position, it being understood that the 5 spring is compressed through placing of the cap in position upon the casing.

I claim as my invention:—

1. Flash lamp structure comprising a casing and a battery cell, a cap for the casing, 10 a compression spring interposed between the cap and said cell, a suspending member pivotally supported by said spring, and means for effecting deflection of said spring from its normally operative position upon movement of said suspending member to a given position.

2. Flash lamp structure comprising a casing and a battery cell, a cap for the casing, 20 a compression spring interposed between the cap and said cell, a suspending member disposed exteriorly of the cap but having a portion extending to the interior of the cap and pivotally supported by the said spring, and means for effecting deflection of said spring from its normally operative position upon movement of said suspending member to a given position.

3. Flash lamp structure comprising a casing and a battery cell, a cap for the casing, 30 a compression spring interposed between the cap and said cell, means in conjunction with said spring for utilizing said spring to hold the cap in position upon the casing, a suspending member, a pivotal connection between said suspending member and the spring, and means for effecting deflection of said spring from its normally operative position upon movement of said suspending member to a given position.

4. Flash lamp structure comprising a casing and battery cells, a cap for the casing, a compression spring interposed between the cap and said cells and having one end fitting within the cap, a suspending member 45 disposed exteriorly of the cap but having a portion extending into the cap and in pivotal connection with said spring, and a catch at one edge of the suspending member for engaging a corner of the cap, that portion of the spring to which the suspending member is connected being of such diameter that it is distorted diametrically when the suspending member is moved to folded position, 50 through camming engagement of the said catch with the cap.

5. Flash lamp structure comprising a casing and battery cells, a cap for the casing, a compression spring interposed between the 60 cap and said cells, a suspending member disposed exteriorly of the cap, and a connection between said suspending member and the said spring for holding the spring in secured relation to the cap.

6. Flash lamp structure comprising a cas-

ing and battery cells, a cap for the casing, a compression spring interposed between the cap and said cells, and means disposed exteriorly of the cap but having a portion extending to the interior thereof, the said portion having connection with the spring to hold it in secured relation to the cap.

In testimony whereof I, the said HARRY T. HIPWELL have hereunto set my hand.

HARRY T. HIPWELL.
